UNITED STATES PATENT OFFICE.

ALFRED H. WILLETT, OF WEST NEW YORK, NEW JERSEY, ASSIGNOR TO AMERICAN ARCH COMPANY, OF NEW YORK, N. Y., A CORPORATION OF DELAWARE.

LOCOMOTIVE-BOILER FURNACE.

1,306,133.

Specification of Letters Patent. Patented June 10, 1919.

Application filed September 28, 1917. Serial No. 193,670.

To all whom it may concern:

Be it known that I, ALFRED H. WILLETT, a citizen of the United States, and a resident of West New York, county of Hudson, and 5 State of New Jersey, have invented certain new and useful Improvements in Locomotive-Boiler Furnaces, of which the following is a specification.

My invention relates generally to improvements in locomotive boiler furnaces, and relates more particularly to improvements in locomotive boiler furnaces of the type provided with a cross wall of refractory material, generally known as a "Gaines" 15 wall; and a co-acting tube supported fire arch or baffle.

The general object of my invention is to provide a fire box of this type, which shall be of low cost; efficient in operation; and 20 which shall be so constructed that it will withstand the severely disruptive forces to which it has been subjected in use, without premature deterioration.

A further object of my invention is to provide a locomotive boiler of the type referred to, in which the various parts thereof shall be so formed and positioned that uniform durability of the whole may be secured to the end of the life of the fire box, and that 30 failures due to premature breaking down of part of the structure may be obviated.

My invention consists generally in the form, construction, arrangement, and coöperation of the parts whereby the above 35 named objects, together with others which will appear hereinafter, are attainable; and my invention will be more readily understood by the accompanying drawings, which illustrate the form of my invention, which I 40 consider the best at the present time.

In said drawings:

Figure 1 is a central, vertical, longitudinal, sectional view of a locomotive boiler furnace embodying my invention.

Fig. 2 is a vertical sectional view substantially on the line 2—2 of Fig. 1, but omitting the grate.

Fig. 3 is a fragmentary plan view of a portion of the fire box directly over the cross wall.

Fig. 4 is a plan view of one of the members of the fire arch.

Fig. 5 is a sectional view substantially on the line 5—5 of Fig. 4.

Fig. 6 is a side elevation of the member 55 shown in Figs. 4 and 5.

Fig. 7 is a rear elevation of one of the members of the fire arch that coöperates with the members shown in Figs. 4, 5 and 6.

Fig. 8 is a plan view of the member of 60 Fig. 7; and

Fig. 9 is a sectional view substantially on the line 9—9 of Fig. 8.

As stated in the opening of the specification, the present invention relates to improvements in locomotive boiler furnaces of the type equipped with a cross wall and a tube supported arch. These walls and arches are usually built of fire brick, which, for various reasons, is the most desirable material. These walls and arches in practice, due to the shaking, jarring and swaying movement of the locomotive, are subjected to very severe forces tending to disrupt the parts. The fire arch or baffle wall is mounted on 75 supporting tubes, which are inclined, and the lower portion of the arch rests upon the upper part of the cross wall. Because of the jarring, shaking and swaying movement of the locomotive, the fire arch tends to move 80 downward along the inclined tubes, and as a result often severs or shears the upper part of the cross wall, and thereafter may slide downward until it butts the flue sheet of the fire box. When such a failure occurs, it not 85 only destroys the brick or bricks severed, but it also has a very disruptive and detrimental effect on the rest of the arch parts, due to the resultant abnormal movement of the various members of the arch.

As will be better understood when the detailed description of the parts is given, I correct and overcome this very serious defect in a very simple but efficient manner to-wit: by so forming, positioning and embodying metallic members in the fire wall and arch construction that the forces tending to sever or shear the upper part of the cross wall are transmitted to the circulation tubes by the metallic members, which at the same time 100 are so protected as to be unaffected by the intense heat of the fire box. Furthermore, my construction is such that no changes in approved fire box construction of the type referred to are required.

Referring now to the drawings:

1 is a locomotive boiler fire box and comprises a flue sheet 2 at its forward end, a

rear sheet, 3, provided with a fuel door or opening, 4; crown sheet, 5; and side sheets 6. The fire box is provided with a grate, 7, of usual construction, but the space occupied by the grate is less than the total length of the fire box. A refractory cross wall, 8, is provided in the forward end of the fire box, the object of which together with arch 9, is to prevent the direct flow of the gases of combustion from the grate to the flues. The cross wall 8 is supported on a bridge or span member 10; is composed of several rows of refractory bricks 11; and rises a considerable distance vertically in the fire box. This wall is preferably provided with a plurality of air conduits, 12, opening at their upper ends, 13, into the fire box. It is not thought necessary to describe the lower part of the cross wall, 8, and its supporting members in detail, since this is of the usual construction.

The arch, 9, extends rearward and upward through the fire box from the upper part of the cross wall, 8, and for the purpose of supporting this arch in position a plurality of spaced water circulating or arch supporting tubes, 14, are provided. These tubes as shown extend between the front and rear water legs, 15 and 16, being curved to enter the water legs at substantially right angles thereto, thus providing a curved portion 17, adjacent the upper part of the cross wall, 8. In fact, I purposely position the cross wall with respect to the curved portions, 17, of the arch supporting tubes to the end that the upper part of the cross wall may engage the under portions of the tubes. The arch 9, as will be seen, comprises a plurality of rows of bricks, 18, which rest upon and extend between adjacent arch tubes and between the side tubes, and the side sheets. Special side bricks, 19, are provided to accommodate themselves to the varying distances between the tube and the side sheet. It is obvious that this arch or baffle wall, 9, occupying a position upon the inclined arch tubes, 14, tends to slide downwardly along the tubes, which action is augmented by the shaking and jarring of the locomotive in use. The bricks, 11, of cross wall, 8, and the various bricks of arch 9, are composed of refractory fire brick, which are best adapted to withstand the intense heat evolved in the fire box, but which are not well adapted to withstand a shearing action.

There is an enormous force exerted on the top of the cross wall by the abutting downward inclined fire arch, 9, which tends to, and has heretofore in practice, frequently severed or sheared the top of cross wall 8, and permitted the entire arch 9 to slide downwardly until it engaged the flue sheet with the detrimental defects before referred to. I overcome this serious defect heretofore prevalent in furnaces of this type, by pro-

viding or capping the upper part of the cross wall, 8, with a plurality of cap members, 20, of a special construction. The construction of members, 20, is well shown in Figs. 4, 5, and 6 wherein it will be noted that 70 the member comprises a base portion, 21, side portions, 22, and back portion, 23. The side portions, 22, extend upward from the bottom portion, 21, a considerable distance, and the back portion, 23, rises still higher 75 than the side portions, and the side portions join the bottom portion in this instance by means of beveled faces, 24. In this manner a recess is formed of such shape that it receives and nicely embraces the special 80 brick, 25, as shown best in Figs. 7, 8, and 9. The member, 20, is composed of metal and it will be noted wedges under the arch supporting tubes, 14, that is to say, the inclined curved side faces, 26, co-act with the under 85 portion of the arch tubes. The special brick, 25, fitting into the metallic member, 20, also has side portions, 27, which extend under the arch tubes behind the metallic member, 20, protecting member 20 from impingement of furnace flames. Thus it will be seen that the pressure or force of the arch tending to sever the top of the cross wall, 8, is transmitted directly to the metallic member, 20, which in turn abuts directly against 90 the arch tubes, 14. It is impossible, therefore, to sever the top portion of the cross wall, and as a result the cross wall and arch continue in proper operative position during 95 their natural life.

When the cross wall, 8, is provided with air ducts as shown, for the purpose of supplying air over the grates, the metallic cap member, 20, is cut away as indicated at 100 30, and the special fire brick, 25, is recessed as 105 shown in 31, to form a duct communicating with the vertical conduits as is shown in the drawings. Of course, if the vertical air ducts are dispensed with, the co-acting recesses of members 20 and 25 also may be 110 omitted.

It should be noted that the metallic member, 20, is completely protected from direct impingement of the fuel gases, and is practically surrounded by refractory material of 115 the fire bricks, being thereby protected from those intense temperatures, which would quickly destroy a metallic member.

In this manner a fire box construction is provided in which the various parts so co-act that an efficient, durable and easily maintained arch and cross wall are provided, and in which failures due to severing of the upper portion of the cross wall are entirely prevented.

I claim:

1. In a locomotive boiler furnace, a plurality of inclined arch tubes, a cross wall, comprising a body portion formed of fire brick and a top portion formed of a plu- 130

rality of metallic members, a fire arch on said inclined tubes, and fire bricks interposed between the metallic top members and the fire arch, said metallic members contacting with the arch tubes and receiving the thrust of the arch.

2. In a locomotive boiler furnace, a plurality of inclined arch tubes, a cross wall provided with a plurality of metallic top 10 members, a fire arch on said arch tubes, and fire bricks interposed between the metallic members and the fire arch, the metallic members and the interposed bricks contacting with the arch tubes and the metallic 15 members receiving the thrust of the arch.

3. In a locomotive boiler furnace, inclined arch tubes, a fire arch on said tubes, a cross wall having a metallic top portion provided with a recess, and a fire brick interposed between 20 the fire arch and the metallic portion adapted to fit into said recess, the fire brick and the metallic portion contacting with the arch tubes and the metallic portion receiving the thrust of the arch.

25 4. In a locomotive boiler furnace, a plurality of inclined arch tubes each having a bent portion, a fire arch supported on the tubes above said bent portions, a cross wall formed with a plurality of metallic top members, said metallic members contacting with

the arch tubes at substantially the point where the bends occur, and having recesses therein, and fire bricks interposed between the arch and the metallic members fitting into the recesses and adapted to transmit the 35 downward thrust of the fire arch to the metallic members.

5. In a locomotive boiler furnace, an inclined fire arch, a cross wall provided with a metallic top member adapted to receive 40 the downward thrust of the arch, said metallic member being protected at least on the fire-bed side thereof from combustion action.

6. In a locomotive boiler furnace, a plurality of inclined arch tubes, a fire arch supported on said tubes, a cross wall formed with a plurality of metallic top members, and fire bricks interfitting with said metallic members and adapted to transmit the downward thrust of the fire arch to the metallic 45 members, said metallic members and bricks contacting with the arch tubes, the cross wall being formed with spaced air conduits and the metallic members and the interfitting bricks being formed with openings 50 communicating with said air conduits.

In testimony whereof, I have hereunto set my hand this 6th day of September, 1917.

ALFRED H. WILLETT.
